(57) **CLAIM**

The ornamental design for a side panel for a computer enclosure, as shown and described.

DESCRIPTION

FIG. 1 is an isometric view of a side panel for a computer enclosure showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an annotated view of FIG. 1;

FIG. 9 is an enlarged, isometric view of an encircled portion IX of the view of FIG. 8;

FIG. 10 is an annotated view of FIG. 4;

FIG. 11 is an enlarged, isometric view of an encircled portion XI of the view of FIG. 10;

FIG. 12 is an annotated view of FIG. 6; and,

FIG. 13 is an enlarged, isometric view of an encircled portion XIII of the view of FIG. 12.
